DESIGN FOR A STOCKING

Jakob Leszczynski and Ruth Johanna Bouscher,
New York, N. Y.

Application May 8, 1943, Serial No. 110,159

Term of patent 7 years

To all whom it may concern:

Be it known that we, Jakob Leszczynski, a citizen of Poland, and Ruth Johanna Bouscher, a citizen of the Free City of Danzig, have invented a new, original, and ornamental Design for a Stocking, of which the following is a specification, reference being had to the accompanying drawing, forming part thereof.

We claim:

The ornamental design for a stocking, as shown.

JAKOB LESZCZYNSKI.
RUTH JOHANNA BOUSCHER.
